UNITED STATES PATENT OFFICE.

JOHN A. FRAMPTON, OF COLUMBUS, OHIO.

FIGURE TOY.

Application filed March 29, 1926. Serial No. 98,334.

This invention relates to figure toys and more particularly to dancing dolls.

An object of the invention is to provide a doll having resilient legs, and so constructed that the fingers of the user may be inserted into the top of the legs to permit manipulation of the doll on a surface in a manner similar to dancing.

A further object is to provide a support for the legs having openings therein for the reception of the fingers.

A still further object is the provision of means for flexibly supporting the head and shoulders to permit movement thereof.

In the accompanying drawings I have shown one embodiment of the invention. In this showing,

Figure 1 is a front elevation,

Figure 2 is a similar view with the clothing and other parts shown in section,

Figure 3 is a horizontal sectional view on line 3—3 of Figure 2;

Figure 4 is a similar view on line 4—4 of Figure 1, and,

Figure 5 is a perspective view of a foot and a foot supporting member.

In constructing the doll I provide a plate 1 which is provided with substantially parallel front and rear edges 2 and 3 and curved sides 4 to simulate the waist portion of a person. This plate is provided with a pair of openings 5 and the material cut out to form the openings is arranged in the form of a bead as at 6. Each of these beads is adapted to receive the end of a coil spring 7, the two coil springs forming the legs of the doll. In the bottom of the coil springs I arrange foot supporting members 8 and plates 9 shaped substantially similar to the

feet of a human being are arranged on these feet supporting members. Above the plate 1, I provide an upright or standard 10 which is secured to the plate adjacent its front edge (see Figure 3). A doll head 11 is mounted over this standard, the doll head being formed of any suitable material and extending downwardly to form the neck and shoulders 12. At the front of the neck I provide a downwardly extending member 13 which is secured to the standard adjacent its lower edge as at 14.

Trousers 15 are arranged on the doll and extend downwardly from the waist plate 1 to a point adjacent the feet. A sweater or other garment 16 is arranged over the neck with the bottom of the garment disposed be-

low the top of the trousers. The arms 17 of the doll may be secured to the upper garment and (see Figure 4) may be formed by spirally wrapping a piece of the material 60 from which the garment is constructed.

In operation, the sweater is lifted at the back and the ends of two of the fingers of a person inserted in the upper leg portions through the openings 5. The doll may then be manipulated over a table, desk or other surface in a manner similar to dancing. By providing the legs 7 formed of coil springs or other resilient material the doll may be caused to assume various grotesque positions. The arrangement of the upper body is such that it permits considerable movement of the head, being secured to the standard 10 at a point adjacent the bottom thereof. The standard, extending up into the 70 head limits this movement to prevent the upper portion of the doll from being broken from its support.

It is to be understood that the form of my invention herewith shown and described is 80 to be taken as a preferred example of the same and that various changes in the shape, size, and arrangement of parts may be resorted to without departing from the spirit of the invention or the scope of the sub- 85 joined claims.

I claim:

1. In a doll of the character described, a plate having a pair of openings, and resilient legs secured to said plate in alignment with said openings, said legs being hollow and open at the top thereof whereby the fingers of the user may be inserted through said openings into the legs to manipulate the doll.

2. In a doll of the character described, a plate having a pair of openings, resilient legs secured to said plate in alignment with said openings, said legs being hollow and open at the top thereof and having feet 100 supporting members secured to the lower ends of said legs, and feet carried by said feet supporting members.

3. In a doll of the character described, a plate having a pair of openings, resilient legs secured to said plate in alignment with said openings, said legs being hollow and open at the top thereof and having feet supporting members secured to the lower ends of said legs, feet carried by said feet 110 supporting members, and a body mounted on the upper side of said plate.

4. In a doll of the character described, a plate having a pair of openings, a pair of resilient legs depending from said plate in alinement with said openings, said legs being hollow and open at the top thereof, a standard extending upwardly from said plate, and a neck and head arranged over said plate and secured to said standard.

5. In a doll of the character described, a plate having a pair of openings, a pair of resilient legs depending from said plate in alinement with said openings, said legs being hollow and open at the top thereof, a standard extending upwardly from said plate, and an upper body member comprising a neck, a head and a downwardly extending body portion, said upper body member being

secured to said standard adjacent its lower end.

6. A toy of the character described comprising a body member and leg members connected thereto, said leg members being resilient and being adapted to partake of universal motion with relation to said body member and said leg members being provided with finger-receiving openings in the portions thereof adjacent the point of junction of said body and leg members whereby the fingers of the user may be inserted into said openings to manipulate said leg members.

In testimony whereof I affix my signature.

JOHN A. FRAMPTON.
